US00D337781S

United States Patent [19]

Suzuki et al.

[11] Patent Number: Des. 337,781

[45] Date of Patent: ** Jul. 27, 1993

[54] LASER BEAM PRINTER

[75] Inventors: **Kimiko Suzuki, Tokyo; Masahiko Kashiwabara, Hiyoshi, both of Japan**

[73] Assignee: **Kabushiki Kaisha Toshiba, Kawasaki, Japan**

[**] Term: **14 Years**

[21] Appl. No.: **712,631**

[22] Filed: **Jun. 10, 1991**

[30] Foreign Application Priority Data

Dec. 10, 1990 [JP] Japan 2-40942

[52] U.S. Cl. **D18/55**

[57] CLAIM

The ornamental design for a laser beam printer, as shown and described.

DESCRIPTION

FIG. 1 is a top, front and right side perspective view of a laser beam printer showing our new design, with paper cassettes pulled out;

FIG. 2 is a front elevational view thereof;

FIG. 3 is a top plan view thereof showing the paper cassettes pushed in;

FIG. 4 is a right side elevational view thereof;

FIG. 5 is a left side elevational view thereof;

FIG. 6 is a rear elevational view thereof; and,

FIG. 7 is a bottom plan view thereof.

FIG. 1

FIG. 2

FIG. 3

FIG. 4

FIG. 5

FIG. 6

FIG. 7
